Primary Examiner — Jeffrey D Asch(57) **CLAIM**

The ornamental design for a mobile terminal, as shown.

DESCRIPTION

FIG. 1 is a front elevational view of a mobile terminal on a dock of my new design;

FIG. 2 is a rear elevational view of the mobile terminal thereof;

FIG. 3 is a left side elevational view of the mobile terminal thereof;

FIG. 4 is a right side elevational view of the mobile terminal thereof;

FIG. 5 is a top plan view of the mobile terminal thereof; and, FIG. 6 is a bottom plan view of the mobile terminal thereof. The Arcci logo on the front above the top right corner of the display in FIG. 1 and on the left of the rear in FIG. 2, which forms a part of the claimed design, is a registered trademark of SHENZHEN NEWPLAN DESIGN CO., LTD.
